UNITED STATES PATENT OFFICE.

FRANK HOWARD CRUMP, OF LOS ANGELES, CALIFORNIA.

BINDER.

1,303,540.

Specification of Letters Patent.

Patented May 13, 1919.

Application filed October 29, 1918. Serial No. 280,178.

To all whom it may concern:

Be it known that I, FRANK H. CRUMP, a citizen of the United States, and a resident of Los Angeles, county of Los Angeles, and 5 State of California, have invented certain new and useful Improvements in Binders, of which the following is a specification.

This invention relates to loose leaf binders and more particularly to transfer binders in which loose leaves are permanently stored. Such binders are ordinarily constructed with either stiff or flexible posts. The stiff posts are secured to the bottom cover plate, the top cover plate being provided with an adjustable clamping member, or else the posts are threaded at one end, the two covers being held together by a nut screwed down over the threaded end of the post. Other binders are provided with flexible U-shaped wires, flat or round, passed through both covers and bent over to hold the two covers together. Both the stiff posts and the flexible posts extend above the top cover, are unsightly, prevent the records being stored neatly and economically and scratch or mar the furniture.

This invention aims to provide a binder which will avoid the necessity of an adjustable clamping member or an unsightly threaded post with a nut or to bend a flexible post to secure the proper adjustment.

Another aim is to provide metal binding strips which may be punched to receive the clamping member after the plates have been 35 bound into the cover thereby facilitating the manufacture of the binder.

Another aim is to provide a binder with no protruding posts or clamping members which will mar the furniture.

Another aim is to provide a binding device with which a record of any thickness may be bound and which will present the appearance of a sewed book.

Another object is to provide a simple 45 means for holding the posts in the bottom cover.

For a full understanding of the invention, reference is to be had to the following description and the accompanying drawings, 50 in which—

Figure 1 is a perspective view of the binder embodying the present invention,

Fig. 2 is a vertical longitudinal section view therethrough taken in a plane with 55 one end of the U-shaped wire,

Fig. 3 is a side view of the U-shaped wire before being twisted,

Fig. 4 is a similar view of a portion of the U-wire after being twisted at the top and bottom,

Fig. 5 is a vertical section through a 60 slightly modified form.

Corresponding and like parts are referred to in the following description and indicated in all views of the accompanying 65 drawings by the same reference characters.

Referring now to these figures, my improved binder contemplates the use of a back 10 and a cover 11, between which the sheets 12 to be bound are placed, each of 70 the said back and cover being flexibly connected by the covering material at 12, with a binder strip through which the fastening members, securing the bound sheets 12, are extended.

The binding or clamping members comprising my invention are each in the form of a flat U-shaped wire 13, the body of which extends along the lower surface of the back of the binder within a groove 80 formed by the corrugated metal binder strip 14 of the back 10. This metal binder strip 14 has openings through which the extensions 15 of the U-wire project as clearly seen by reference to Figs. 1 and 2, which 85 extensions may be of various lengths, and either removable with respect to the back strip 14 or secured in connection therewith by twisting the major portions of the extensions 15 at right angles to lock the same 90 in connection with the back strip, as clearly seen in Fig. 2.

The binder strip of the cover 11 has a metal plate 16 beneath a wooden, cardboard, or other strip 17, the plate 16 having openings conformable to the shape of the extensions 15 of the clamping members, and the strip 17 having enlarged openings within which the extremities 18 of said extensions may be twisted at or about right angles in 95 order to lock the parts in connected relation. The extensions 15 of the clamping members are preferably cut off below the level of the upper surface of the strip 17 at the same time the extremity 18 is twisted, 100 and it is to be observed that this structure not only admits of the clamping of any desired number of sheets 12 within a wide range, but obviates all projecting parts as in the majority of binders now in use, which 110

come into contact with and scratch, mar or otherwise destroy the appearance of a desk or other supporting surface upon which the binder is used.

- 5 The extensions 15 of the clamping members need not be twisted to secure the same in connection with the binder strip 14 of the back 10, and if untwisted as seen at 15^a in connection with the clamping member 10 13^a of Fig. 5, it is obvious the clamping member may be readily withdrawn for the substitution of clamping members having extensions of various lengths. Furthermore, as seen from Fig. 5, the binder may consist 15 of plain cardboard back and cover binder strips 19 and 20 adjacent the openings through which strips are washers 21 and 22 having openings through which the extensions 15^a are projected. The washer 22 20 may for instance be cup-shaped or plano-concave, as shown, in either instance, providing for the twisting of the extremities 23 of the extensions 15^a within the limits of the washer so as to avoid the projecting 25 twisted raw edge of the extension.

The method of operation is as follows: Having placed the sheets to be bound over the free ends of the U wire, the top cover is also slipped over and pressed down hard 30 and with wire nippers the wire is twisted at an angle, preferably a right angle, and subsequently cut off by the same implement. The head thus formed prevents the top cover coming off and the reinforcement above the 35 plate provides a recess for the head which prevents it protruding above the cover. The binder may then be turned over and moved freely over a desk without marring it and may be stored as neatly and economically as 40 a sewed book.

I claim:

1. In a binder, spaced leaf-confining members, a flat U-shaped resilient wire carried by and projecting through one of said members, the other member being provided with 45 apertured means having openings conforming to the shape of and receiving the free ends of the U wire, said ends being twisted

at their extremities and forming locking heads of greater width than the width of 50 the said openings.

2. In a binder, spaced leaf-confining members, a flat U-shaped resilient wire carried by one member through openings therein, the extension of the wires being twisted 55 laterally at right angles thereby securing the wires to said member, the other member being provided with openings formed at right angles to the openings in the first member and into which the free ends of the 60 wires are received, said ends being twisted at an angle and forming heads of a width greater than the width of the openings.

3. A binder including a back and cover having leaf confining members of which the 65 member of the back is formed of corrugated metal providing grooves, the said leaf confining members having slotted openings, and a clamping member formed of a flat U-shaped wire seated along and within one of 70 the grooves of the leaf confining member of the back, the extensions of which wire are mounted through the openings of the leaf confining members and twisted to secure the 75 parts in locked relation.

4. A binder having a back and a cover provided with leaf confining members, one of which consists of a corrugated metal strip and the other of which has a metal strip and a covering strip overlying said metal strip, 80 said metal strips of the two leaf confining members having slotted openings, and a clamping member consisting of a flat U-shaped wire disposed along and within one of the grooves of the corrugated strip, and 85 having its extensions projecting through the openings of the two metal strips, the extremities of said extensions being twisted to secure the parts in locked relation, and said covering strip having openings forming recesses within which the twisted extremities 90 of the wire are housed.

FRANK HOWARD CRUMP.
